UNITED STATES PATENT OFFICE.

EDWARD T. FRAIM, OF LANCASTER, PENNSYLVANIA.

PADLOCK.

SPECIFICATION forming part of Letters Patent No. 768,741, dated August 30, 1904.

Application filed September 12, 1903. Serial No. 172,945. (No model.)

To all whom it may concern:

Be it known that I, EDWARD T. FRAIM, a citizen of the United States, residing at Lancaster, in the county of Lancaster and State 5 of Pennsylvania, have invented a new and useful Padlock, of which the following is a specification.

The invention relates to improvements in padlocks.

10 The object of the present invention is to improve the construction of padlocks and to provide a simple and comparatively inexpensive one of great strength and durability provided with a seamless shell or outer casing and adapted to be assembled and firmly secured together without perforating such shell or outer casing for the reception of rivets or other fastening devices.

15 A further object of the invention is to provide a padlock of this character which when completed will have the rivets practically concealed and which will present an imperforate rivetless appearance.

20 Another object of the invention is to provide a padlock adapted to dispense with the ordinary rivets and similar fastening devices for connecting the parts together and to enable the rotary key-guide to be readily mounted on the bottom of the padlock.

25 Furthermore, the invention has for its object to improve the construction and manner of mounting the spring-actuated bolt for engaging the shackle of the padlock and to permit the bolt to be quickly placed in position 30 in assembling the parts of the padlock.

35 With these and other objects in view the invention consists in the construction and novel combination and arrangement of parts herein-after fully described, illustrated in the accompanying drawings, and pointed out in the claims hereto appended, it being understood that various changes in the form, proportion, size, and minor details of construction within the scope of the claims may be resorted to 40 without departing from the spirit or sacrificing any of the advantages of the invention.

45 In the drawings, Figure 1 is a perspective view of a padlock constructed in accordance with this invention. Fig. 2 is a plan view of

the same. Fig. 3 is a reverse plan view. Fig. 4 is a vertical longitudinal sectional view. Fig. 5 is a vertical transverse sectional view on the line 5 5 of Fig. 4. Fig. 6 is a horizontal sectional view on the line 6 6 of Fig. 4. Fig. 7 is a detail perspective view of the inner 55 vertically-divided casing. Figs. 8 and 9 are detail views of the sections thereof. Fig. 10 is a detail perspective view of the sliding bolt. Fig. 11 is a detail perspective view of the bottom cap. Fig. 12 is a detail view of the key. 60

Like numerals of reference designate corresponding parts in all the figures of the drawings.

1 designates an outer casing consisting of a seamless shell substantially elliptical in horizontal sectional view, as illustrated in Fig. 6 of the drawings, and preferably constructed of steel; but the outer casing may be made of any other suitable material, as will be readily understood, and the shape may be varied, if 70 desired. The outer shell or casing, which is imperforate, as illustrated in Fig. 1 of the drawings, receives an internal body structure or casing 2, which is provided with a top for engaging the upper edges of the outer shell 75 or casing and which is connected with a cap 3, which closes the bottom of the outer shell or casing. The inner casing, which forms a supporting-frame for the locking or shackle-engaging mechanism, is composed of vertical 80 laterally-separable members or sections 4 and 5, the inner casing being divided longitudinally, as clearly shown in Figs. 7 to 9, inclusive. The sections which form the sides of the inner casing are provided at their tops 85 with horizontal flanges or sections 6 and 7, which constitute the top of the padlock-body. The horizontal sections 6 and 7, which are cast integral with the sections of the inner casing, form a cap for engaging the upper 90 edges of the outer shell or casing, and they have straight inner edges 8, which abut when the sections of the inner casing are fitted together, as illustrated in Fig. 7 of the drawings. The outer edges of the horizontal sections of the top or cap are curved or partially rounded at their outer edges at each end to conform to the configuration of the outer 95

shell or casing, and they are provided at their inner edges with end recesses 9 to provide spaces for a shackle 10.

The sections 4 and 5 of the inner casing are provided at their lower ends with integral vertically-disposed rivet-posts 11, which pass through perforations 12 of the bottom cap 3, which is rounded at the ends to conform to the configuration of the outer shell or casing and which is provided at its ends with inwardly or upwardly extending approximately semicircular flanges 13, spaced from the edges of the bottom cap and fitting within the lower end of the outer shell or casing, as clearly shown in Fig. 4 of the accompanying drawings. The inner casing, which extends through the opening of the outer shell or casing, engages the upper edge thereof and is provided with the said top or cap portion for engaging the upper edges of the outer shell or casing, and when the bottom cap or piece 3 is secured to the lower end of the inner casing by the integral rivet-posts the inner and outer casings are securely connected. By this construction the ordinary rivets and pins are dispensed with, and it is unnecessary to drill or otherwise perforate the seamless outer casing or shell for the passage of the fastening means for securing the inner casing to the same. When the posts 11 are riveted to the bottom cap or piece, the latter presents a smooth outer face, and in the finished lock the outer or lower ends of these posts are practically concealed by the polish or finish, and the lock presents the appearance of a rivetless structure.

In order to enable the inner casing to fit tightly within the outer shell or casing and firmly clamp the same, the sections of the inner casing are provided at their upper ends adjacent to the sections of the top cap with wedge-shaped lugs 14, presenting outer inclined edges which extend downward and inward, as clearly shown in Fig. 5, whereby when the inner casing is drawn into the outer casing the parts will be firmly wedged together. These wedge-shaped lugs also serve to brace the sections 4 and 5 of the inner casing at the outer portions of the sections or pieces of the top cap.

The section 5 of the inner casing is provided with studs 15 and 16, having reduced outer ends, forming shoulders and fitting in perforations 17 and 18 of the section 4. These studs 15 and 16 operate to space the sections 4 and 5, which are also provided with top lugs 19, and the latter fit together and are provided with opposite notches 20, forming a socket when the parts are assembled and adapted to receive the end of a key 21. The key 21 is adapted to actuate a sliding bolt 22, and the section 5 is provided below the lugs or enlargements 20 with vertical flanges 23, between which are arranged horizontal lugs or

flanges 24 and 25. The other section, 4, is provided with a bottom flange 26, which fits against or is arranged contiguous the adjacent upright flanges 23. The horizontal flanges 25 and 26 are notched, as shown, to provide a passage for the key 21, which is provided with suitable notches to clear the flanges or lugs to enable it to be rotated sufficiently to actuate the sliding bolt 22. Any number and arrangement of flanges, projections, or lugs may be provided, as will be readily understood. These lugs, flanges, and projections are also located at points between the slideable bolt and the keyhole of the lock, and thereby form guards for preventing an instrument from being introduced into the lock for operating the bolt. Should an instrument or tool be introduced into the keyhole, it would be impossible to move the same sufficiently to operate the bolt. The stud 15 forms the pivot of the shackle and passes through a perforation at one end of the same, as clearly shown in Fig. 4, and the other end of the shackle is provided with a recess, forming a shoulder for engagement with the sliding bolt. One end of the shackle is arranged in one of the end recesses of the top cap and the other end of the shackle is adapted to project through the other end recess for engaging the slideable bolt, and when the latter is withdrawn from such engagement the shackle is free to open or swing outward in the usual manner. The slideable bolt, which has a beveled head or engaging portion 27, is provided with oppositely-disposed laterally-extending lugs 28, arranged in opposite horizontal slots 29 of the sections of the inner casing. The slots, which receive the laterally-extending lugs of the slideable bolt, permit the latter to reciprocate, and the said bolt is positively retained in position when the inner and outer casings are assembled, and it is impossible for the bolt to become accidentally displaced. The bolt is actuated by a spring 29^a, and it has an opening 30, enlarged at one side to form a shoulder and adapted to receive the key, which when rotated engages the shoulder, and thereby reciprocates the bolt against the action of the spring 29^a. The spring 29^a, which is approximately V-shaped, is provided with two arms and has a coil 30^a at the bottom to receive the stud 16. The inner arm, which engages the inner or rear end of the bolt, is substantially straight and the other arm, 31, which engages a heel or extension 32 of the shackle, bears against a stud 33, as clearly shown in Fig. 4, in order to secure the necessary stiffness and to prevent the spring from rotating on the stud 33. When the parts are assembled, the spring is held against lateral movement by a lug or projection 34 extending from the section 4 and terminating short of the section 54.

The bottom cap is provided with a circular opening or aperture 35, in which is arranged

a rotary key-guide 36, consisting of a disk, rabbeted at its periphery to provide a reduced portion to fit in the aperture and to form a projecting flange 37 for engaging the inner face of the bottom cap, which is provided with tongues or lugs 38. The tongues or lugs 38, which are formed integral with the bottom cap, are bent inward over the inner or upper face of the rotary keyhole-guide, whereby the latter is retained in position on the bottom cap 3. The upper face of the bottom cap is provided at the aperture with an annular recess to receive the flange of the rotary key-guide, and the inner or upper face of the latter is substantially flush with the inner or upper face of the bottom cap-piece. The key-hole-guide is provided with a slot which is shaped to conform to the configuration of a key, which may be corrugated, as indicated in Fig. 12 of the accompanying drawings. In assembling the parts the tongues or lugs of the bottom cap may be quickly bent inward over the rotary key-guide, and while only two tongues or lugs are illustrated in the accompanying drawings any number may be employed for retaining the key-guide in position.

In assembling the parts of the lock it is only necessary to rivet the posts of the inner casing to the bottom cap and bend down the tongues of the latter, and it will be apparent that a large number of locks may be put together in a comparatively short time, and that owing to the rivetless structure a lock of great strength and durability is secured. Furthermore, the single riveting of the post of the inner casing operates to fasten the top, the bottom, and inner and outer casings together. Also when the parts are assembled there is no liability of the movable parts becoming accidentally displaced.

Having thus fully described my invention, what I claim as new, and desire to secure by Letters Patent, is—

45 1. A lock comprising an outer shell or casing open at both ends, an inner frame or casing adapted to support the locking mechanism and extending through the outer shell or casing and carrying a cap for closing the casing at one end of the opening thereof, and a cap covering the other end of the opening and secured to the adjacent end of the inner casing, whereby the inner and outer casings and the caps are held together, substantially as described.

2. A lock comprising an outer shell or casing, an inner casing extending through the outer shell or casing and carrying a cap for closing the top of the outer shell or casing, said inner casing being adapted to receive the locking mechanism and provided at the bottom with integral rivet-posts, and a bottom cap secured to the inner casing by the rivet-posts thereof and closing the bottom of the outer shell or casing, substantially as described.

3. A lock comprising an outer shell or casing, an inner casing adapted to support the locking mechanism and provided with means for engaging the outer shell or casing at one end of the opening thereof, a cap secured to the inner casing and engaging the outer shell or casing at the other end of the opening thereof, and a wedge-shaped lug carried by one of the casings and engaging the other, whereby the outer casing is firmly clamped on the inner casing, substantially as described.

4. A lock comprising an outer shell or casing, an inner casing fitting within the outer casing and provided with laterally-extending wedge-shaped lugs engaging the outer shell or casing, and caps closing the opening of the outer shell or casing at the ends thereof, one of the caps being integral with the inner casing and the other cap being secured to the same, substantially as described.

5. A lock provided with an outer casing open at both ends, and an inner casing adapted to receive and support the locking mechanism and provided with means for engaging and closing the outer casing at the ends thereof, one of the closing means being carried by the inner casing and the other being secured to the same, substantially as described.

6. A lock comprising an outer casing, an inner casing divided longitudinally to form sections, said sections being provided at one end with integral portions for engaging and closing the outer casing, and means secured to the other end of the sections for engaging and closing the outer casing, substantially as described.

7. A lock comprising an outer casing, an inner casing adapted to receive the locking mechanism and divided longitudinally and provided with a sectional cap for closing the outer casing at one end, and a cap secured to the inner casing for closing the other end of the outer casing, substantially as described.

8. A lock comprising an outer casing having a vertical opening, an inner casing adapted to receive the locking mechanism and comprising a plurality of sections enlarged at one end to form a sectional cap for closing one end of the opening of the outer casing and provided at the other end with rivet-posts, and a cap secured to the rivet-posts and closing the adjacent ends of the opening of the outer casing, substantially as described.

9. A lock comprising an outer casing having a vertical opening, an inner casing adapted to receive the locking mechanism and provided with a plurality of vertical sections enlarged at the top to form a sectional cap for the outer casing, and a bottom cap closing the bottom of the outer casing and secured to the lower end of the inner casing, substantially as described.

10. A lock comprising an outer casing having a vertical opening, an inner casing provided with a plurality of vertical sections sep-

arable to receive the locking mechanism, and provided at their upper ends with horizontal cap-sections closing the upper end of the outer casing, said inner casing being provided at its bottom with rivet-posts and having wedged-shaped lugs for engaging the outer casing, and a bottom cap closing the lower end of the outer casing and secured to the inner casing by the rivet-posts thereof, substantially as described.

11. A lock provided with inner and outer casings, the inner casing being composed of sections each having a slot, and a bolt slidable in the slots when the sections are assembled, substantially as described.

12. A lock comprising an outer casing, an inner casing adapted to receive and carry the locking mechanism and divided longitudinally to form sections, said sections being provided at one end with a cap for closing one end of the outer casing, and a removable cap for closing the other end of the outer casing, said cap being connected to the inner casing, substantially as described.

13. A lock comprising an outer casing open at both ends, an inner casing divided longitudinally to form sections carrying the locking mechanism, and means for closing the ends of the outer casing, said means being connected to the inner casing, substantially as described.

14. A lock comprising inner and outer casings, the inner casing being composed of sections each of which is provided with a slot forming ways, and a slidable bolt arranged within the inner casing and guided by the slots thereof and being retained in the slots by the outer casing, substantially as described.

15. A lock comprising an outer casing, a sectional inner casing fitting within the outer

casing and provided with opposite slots and having means for engaging the outer casing at the ends of the opening thereof, one of the means being integral with the inner casing and the other being secured to the same, and a slideable bolt having laterally-extending lugs arranged in the slots of the inner casing, substantially as described.

16. A lock comprising an outer shell or casing, and an inner casing fitted within the outer casing and composed of two sections formed by a division of the inner casing longitudinally thereof, a stud connecting the two sections of the inner casing together, and a shackle pivoted on said stud and held between the sections of the inner casing.

17. A lock comprising an outer casing, and an inner casing fitted within the outer casing and divided longitudinally to form sections, said sections being provided with opposite end recesses at the top, said recesses being adapted to receive the free and pivoted ends of the shackle, and a stud or pivot connected with the sections and located in one of the end recesses and forming the pivot for the shackle, whereby the shackle is held at both ends between the sections of the inner casing.

18. A padlock having a seamless sheet-metal case, an internal body structure carrying the working parts of the lock, an end plate, and means for securing the end plate to the body structure, said means being formed integral with one of the parts and engaging the other.

In testimony that I claim the foregoing as my own I have hereto affixed my signature in the presence of two witnesses.

EDWARD T. FRAIM.
